UNITED STATES PATENT OFFICE.

FRANK EGON NEITZEL, OF SAN FRANCISCO, CALIFORNIA, ASSIGNOR TO BETHLEHEM SHIPBUILDING CORPORATION, A CORPORATION OF DELAWARE.

MULTIPLE-SPINDLE DRILL.

Application filed March 12, 1921. Serial No. 451,737.

To all whom it may concern:

Be it known that I, FRANK EGON NEITZEL, a citizen of the United States, residing at San Francisco, county of San Francisco, State of California, have invented a new and useful Multiple-Spindle Drill, of which the following is a specification.

In my prior application filed July 31st, 1919, Serial No. 314,510, I have illustrated and generically claimed a novel construction of multiple spindle drill, the claims being directed more particularly to the multipole spindle drill, *per se*, while my present invention is directed more particularly to the feeding and controlling mechanism for the work table.

With the above in view, my invention comprehends a novel construction of multiple drill which is especially designed for drilling the holes for tubes in boiler drums, although as is apparent, it can be employed in all cases wherein it is desired to simultaneously drill or ream a multiplicity of holes.

It further comprehends a novel construction and arrangement of a drill head, novel means for mounting the drill heads so that they may be brought into closely spaced relationship, novel driving mechanism for the spindles carried by the drill heads and a novel construction and arrangement of mechanism for controlling the spindle driving mechanism.

Other novel features of construction and advantage will hereinafter more clearly appear in the detailed description of the invention.

For the purpose of illustrating one manner of carrying out my invention in practice, I have shown in the accompanying drawings a typical embodiment of it which in practice will give satisfactory and reliable results. It is, however, to be understood that this embodiment is typical only and that the various instrumentalities of which my invention consists can be variously arranged and organized and that the invention is not limited to the precise arrangement and organization of these instrumentalities as herein set forth.

Figure 1 represents, in front elevation, a multiple spindle drill, embodying my invention.

Figure 2 represents a top plan view of the drill.

Figure 3 represents an end elevation of the drill, viewed from the left-hand side of the machine.

Figure 4 represents an end elevation of the drill, viewed from the right-hand side of the machine.

Figure 5 represents, in perspective, a tripping device employed and certain of its adjuncts.

Figure 6 represents, on an enlarged scale, an end elevation of certain parts seen at the left-hand side of the machine.

Figure 7 represents a plan view, partly in section, of certain features of construction at the left-hand side of the machine.

Figure 8 represents a section on line 8—8 Figure 7.

Figure 9 represents, in perspective, and in detached position, a nut employed which is shown in assembled position in Figure 8.

Figure 10 represents a section on line 10—10 Figure 2.

Figure 11 represents a section on line 11—11 Figure 1.

Figure 12 represents an end elevation, partly in section, of certain features of the table controlling mechanism.

Figure 13 represents a sectional view of a portion of the drum seen in Figure 12.

Figure 14 represents a top plan view of a stop member seen in Figures 12 and 13.

Figure 15 represents, in sectional elevation, a bolt and the stop which it carries.

Figure 16 represents a bottom plan view of the construction seen in Figure 15.

Figure 17 represents a section on line 17—17 of Figure 2, showing more particularly the manner in which the drum and certain of its adjuncts are mounted.

Figure 18 represents a section on line 18—18 of Figure 19.

Figure 19 represents a section on line 19—19 of Figure 18.

Figure 20 represents a section on line 20—20 of Figure 1, showing more clearly the manner in which the spindles are mounted and driven.

Figure 21 represents a section on line 21—21 of Figure 1.

Figure 22 represents a section on line 22—22 of Figure 1.

Figure 23 represents, in sectional elevation, another embodiment of my invention wherein spacing elements are employed between the spindle sockets.

Figure 24 represents, in perspective, a spacing element seen in Figure 23.

Figure 25 represents a section on line 25-25 of Figure 1 showing more clearly, 5 on an enlarged scale, the manner in which the drill spindles are mounted and driven.

Figure 26 represents, in front elevation, the feed gear box and certain of its adjuncts.

10 Figure 27 represents a section on line 27-27 of Figure 26.

Figure 28 represents a section on line 28-28 of Figure 1, showing more clearly 15 the friction feed, and the manner in which it is controlled.

Figure 29 represents a section on line 29-29 of Figure 27.

Figure 30 represents a section on line 30-30 of Figure 29.

20 Figure 31 represents a section on line 31-31 of Figure 29.

Figure 32 represents a section on line 32-32 of Figure 30.

25 Similar numerals of reference indicate 25 corresponding parts.

Referring to the drawings.

The framework of the machine.

30 The framework of the machine consists of 30 a base or foundation 1 to which are connected side frames 2, braced at their upper end by means of a cross-beam 3 of structural metal of any desired shape. The base 1 is provided with laterally extending tracks 35 4, see Figures 1 and 2, which extend outwardly beyond the base and are supported at their outer ends by brackets 5 connected to the base. The tracks are adapted to have mounted on them a work carrying table 6, 40 having the depending ribs 7, see more particularly Figure 1, which are guided in the slots 8 in the track 4.

45 The table 6 is provided with means for actuating it, and such means will be hereinafter fully set forth.

50 The base of the machine carries a main driving motor 9, see Figure 4, the shaft of which is provided with a pulley 10, around which passes a belt 11, which also passes 55 around a compound pulley 12 which is mounted on a counter-shaft 13 journaled in the side frames.

55 14 is a belt which passes around the pulley 12 and also around a compound pulley 15 mounted on a shaft 16 carried by a side frame 2. A belt 17 passes around the pulley 15 and around a pulley 18 mounted on a shaft 19 which also has mounted on it a pulley 20, around which passes a belt 21, 60 which also passes around a pulley 22, mounted on a shaft 23 journaled in the machine framework.

The feed gear box.

65 The shaft 23 extends into the feed gear

box 24 which is carried by the cross beam 3, which connects the side frames 2. The shaft 23 is provided with a pinion 25, see Figure 29, which meshes with a gear 26, the hub of which is loosely mounted on a shaft 70 27 journaled in the gear box.

The shaft 23 is also provided with a worm 75 28 which meshes with a worm wheel 29, see Figure 30, mounted on a shaft 30, which latter also has mounted on it a worm 31, which meshes with a worm wheel 32, the hub of which is loosely mounted on the shaft 27. The hub of the gear 26 is provided with a clutch face 33, which co-operates with a clutch face 34 of a clutch collar 35, which latter is also provided with a clutch face 36, which co-operates with a clutch face 37 of the worm wheel 32, so that the shafts 23 and 27 can be operatively connected with each other. 85

The clutch collar 35 is slidingly mounted on and keyed to the shaft 27 to rotate in unison with it and the clutch collar 35 is provided with a yoke 38, which is fulcrumed at 39 and has an arm 40, which extends through a slot in the gear box 24 and has its outer end extending into a slot 41 in a longitudinally slidable rod 42, which is loosely mounted on the gear box. 90

The rod 42 has fixed to it a rack sleeve 43, 95 see Figure 28, with which engages a rack segment 44 fixed to a rock shaft 45 journaled on the feed gear box 24. An actuating arm 46 is secured to the forward end of the rock shaft 45. The rock shaft 45 has loosely 100 mounted on it an actuating lever 47 to which is connected one end of a slide bar 48 guided in a sleeve 49 on the feed gear box 24, see Figures 1 and 26.

The bar 48 is provided with an inclined or bevelled face 50, see more particularly Figure 26, which merges into a straight face 51, and the free end of the slide bar 48 is provided with a downwardly extending lug 52. 105

53 designates a roller which normally engages the straight face 51, and this roller is carried by a spring-pressed plunger 54, which is keyed in a bracket 55 so as to have only longitudinal movement, and a spring 56 is provided which tends to retain a stop arm 57 on the plunger in its upward or operative position and in the path of an arm 58 which extends through a slot 59 in the feed gear box and is connected to the yoke 38, see more particularly Figure 30. 110

I provide a holding device for such yoke 38, which consists of a plunger 60, see more particularly Figure 30, slidable in a sleeve 61 extending through a wall of the feed gear box 24. A spring 62 is provided one end of which abuts against the plunger while its opposite end abuts against an adjusting screw 63 in engagement with the sleeve and provided with a lock nut 64. The plunger 120

bears against a roller 65 carried by the yoke 38. The plunger 60 is provided at its forward end with a wedge-shaped face 211 which contacts with the roller 65 slightly off center so that it tends to hold the arm 58 of the yoke 38 in contact with the stop arm 57, thus retaining the yoke in its neutral position. The plunger 60 is prevented from rotating by means of a pin 212 which extends into a keyway 213 in the plunger 60.

The shaft 23, see Figures 26, 28 and 29, has mounted on it a friction gear 66, and the shaft 27 has mounted on it a friction gear 67.

As will be best understood by reference to Figure 28, a rock shaft 68 is suitably journaled on the feed box 24 and in a bracket 69, and is provided with a rock arm 70, the outer end of which carries a friction gear 71, which is adapted to be brought into operative engagement with the friction gears 66 and 67 by means of an arm 72, one end of which is fixed to the rock arm 68. The front end of the arm 72 extends in front of the machine as seen in Figure 1 and is provided with a manually actuated cable 73. The arm 72, see Figure 28, is maintained in its inoperative position by means of a spring 74, one end of which is connected to the arm 72, while its opposite end bears against a suitable fixed point such as for example the cross beam 3.

The shaft 27, see Figures 1 to 4 inclusive, and Figure 20, is provided at each end with a gear 75, which meshes with a gear 76 fixed to a vertically disposed feed screw 77, provided with a collar 78 mounted between ball bearings 79, which are carried by a side frame 2, see Figure 20.

The feed screws 77 pass through nuts 80, see Figures 20 and 21, which are secured by means of fastening devices 81 to a cross rail 82 which is vertically reciprocable and is recessed as at 83, see Figure 21, to receive the guides 84 extending from the side frames 2. The guide plates 85 are connected to the cross rail 82 by means of bolts 86 so that the cross rail 82 is properly guided in its upward and downward movements.

87 designates a spindle carrying head or drill support which is mounted in a dovetailed keyway or guide 88 on the cross rail 82, and in order to provide for the lateral adjustment of the drill head support 87 an adjusting screw 89 is provided which is in threaded engagement with a nut 90 which is fixed to the drill head support 87, see Figure 22.

60 *Mechanism for laterally adjusting the spindle carrying head.*

The free end of the adjusting screw 89 is provided with a grasping handle 91, see Figures 1 and 4, by means of which it may be rotated, it being seen from Figure 21 that

the adjusting screw 89 is provided with set collars 92 located on opposite sides of the portion in which it is journaled to prevent longitudinal movement of the adjusting screw 89 with respect to the cross rail 82.

70

The drill heads and their spindles.

93 designates the spindles, rotatably mounted in their respective drill heads 94 or 100, see Figures 20 and 25, antithrust 75 bearings 95 being positioned between each spindle and its drill head. Certain of the drill spindles 93 have at their upper ends the gears 96 which are retained in position by the nuts 97. The gears 96 mesh with the spiral gear 98 journaled in the rearwardly extending brackets 99 of the drill head 94.

The drill heads 100 are of the same construction as the drill heads 94 except that the off set brackets 101, see Figure 20, extend forwardly instead of rearwardly. The spindles 93 of the drill heads 100 are provided with gears 102 which mesh with a spiral driving gear 103 journaled in the brackets 101. The drill heads are fixed in

their adjusted position by means of set screws 104. The gears 98 and 103 are journaled in brackets carried by the cross rail 82, see Figures 1 and 2. The spindle driving gear 103 has fixed to it a gear 105 95 which meshes with a gear 106 on the driving gear 98. The driving gear 103 is journaled in brackets 107 and is provided with pulleys 108 around one of which passes the belt 17 which also passes around idlers 109, see 100 Figure 4, carried on the cross rail 82 so that a uniform arc of contact for the belt is maintained on the driving pulley for the drill spindles.

A driving belt 110 at the opposite end of the machine, see Figure 3, passes around the other spindle driving pulley 108 and around idlers 111, carried by the cross rail 82, and also around pulleys 112 and 113, the pulley 112 being carried by a stud shaft 114 and the pulley 113 being mounted on a shaft 115

extending from a side frame 2. The pulley 113 is a compound pulley and has passing around it a belt 116 which also passes around a pulley 117 mounted on the countershaft 115 110 115 13, see Figure 3, which latter as before explained is driven from the main driving motor 9, see Figure 4.

The side frames 2 are provided with brackets 118 which carry sheaves 119 over which pass cables 120 connected to the cross rail 82 and to counterbalance weights 121, see Figures 2, 3 and 25.

The drill heads 94 and 100 are apertured to receive a laterally extending rod 122, see 125 Figures 1, 20, 23 and 25, which is secured in fixed position by means of set screws 123. Spacing members 124, see Figure 24, which are preferably U-shaped, are placed on the rod 122 between adjacent drill heads. One 130

end of the rod 122 is headed and the other end is provided with threads to receive the nuts 125, one of which serves as a lock nut.

5 *Actuating means for the work table.*

The shaft 115, see Figures 3, 6, 7 and 10, is continuously running and carries a spiral pinion 126 always in mesh with a spiral gear 127 loosely mounted on a shaft 128, see 10 Figure 10, which at its rear end is provided with a spiral pinion 129 engaging a spiral gear 130 fixed to a shaft 131, see Figure 2. This shaft 131 has on it bevel gears 132 meshing with bevel gears 133 on the worm 15 shafts 134 journalled on the base 1 and engaging nuts 135 carried by the work table, see Figure 11.

In order to provide a quick return of the work table, I employ a motor 136, the shaft 20 of which has a gear 137 in mesh with a gear 138 fixed to a shaft 139 suitably journalled and provided with a clutch collar 140, the clutch face of which engages with a clutch member 141 fixed to the shaft 128, such engagement being controlled by means of a manually actuated clutch lever 142, see Figures 1, 2, 3, 7 and 10.

The hub of the gear 127 has fixed to it a clutch member 170, see more particularly 30 Figures 7 and 10 adapted to be engaged by a clutch collar 143 keyed to the shaft 128 and against which bears one end of a spring 144, the other end of which bears against a set collar 145 adjustable on the 35 shaft 128. The clutch collar 143 has a clutch arm 210 extending laterally from it and connected to a longitudinally slidable shifter rod 146 mounted in standards 147 and having a threaded portion 148, see 40 Figure 8, on which is adjustably secured by means of nuts 149 a rod shifting member 150, see also Figure 9. The member 150 is provided with a cam shaped lug 151. The free end of the shifting rod is faced 45 off or bevelled, as at 152, so that the overhanging portion may be deflected as hereinafter described. The free end of the rod 146 is engaged by a tripping device which will now be described, see Figures 18 and 50 19. A stand 153 has a vertically disposed 55 aperture 154 through it which is of reduced diameter at 155 to limit the upward movement of a block 156 connected to a trigger or plunger 157 which is normally held in its raised position by means of a spring 158 and is keyed to the stand.

The trigger has an apertured head 159 in which is mounted a latch 160 having a longitudinal groove 161 into which extends 60 a screw 162 to prevent rotation of the latch. The latch has a reduced portion extending through the rear end of the trigger head and provided with a nut 163. A spring 164 is interposed between a portion of the 65 latch and the trigger of plunger head to

normally retain the latch in its forward position.

The trigger or plunger head has fixed to it a ring 165 having a laterally extending toe 166 positioned beneath the operative end of the latch 160 and having its top face bevelled.

The stand 153 is apertured as at 167 to receive the rounded end of a rock arm 168 which extends through an aperture 169 in the block 156. The rock arm 168 has its rear end connected to a rock shaft 171, see more particularly Figures 2, 7 and 12, journalled in standards 172. The rock shaft 171 has a rock arm 173 connected to one end of a longitudinally adjustable rod 174 pivotally connected at 175 to a lever 176 one end of which is pivotally supported at 177 on a side frame 2, while the other end of such lever is connected at 178 to a bar 179, see Figure 3, which latter is pivoted at its upper end to one end of a link 180. The other end of the link 180 is pivotally supported on the side frame 2.

The bar 179 carries a thrust member 181 having its top face bevelled, see Figures 3, 5 and 12, and the member 181 is in the path of a latch or trip member 182 carried by the cross rail 82 and having a cam face 183. The shifting rod 146 travels on a suitably supported roller 184.

The shaft 128 has mounted on it a worm 185, see Figure 10, which meshes with a worm gear 186 keyed to a shaft 187 suitably journalled above the base 1. Slidingly mounted and keyed to the shaft 187 is a threaded sleeve 188, see Figure 17, which moves longitudinally in a fixed nut 189. Fixed to the sleeve 188 is a drum 190 having in its periphery spiral T-slot grooves 191 forming a coarse pitch screw to receive the rectangular shaped heads 192 of the threaded studs 193, see Figures 13, 14, 15 and 16.

These studs receive the nuts 194 which secure them in adjusted position on the drum and form stops. The nuts 194 are grooved as at 195 to receive a suitable tool for securing them in position. Belt tighteners 196 and 197 are provided for the belts 115 110 and 116, respectively, see Figure 3. Belt tighteners 198 and 199 are provided for the belts 14 and 17 respectively, see Figure 4. 200 is a valve controlled apertured pipe supported by hangers 201 from the head 87, see Figure 1, and leading from a source of fluid supply (not shown). The spindles 93 carry the working tools 202 such as for example, the drills shown in the drawings.

The clutch lever 142, see Figure 6, has connected to its lower end, as at 203, one end of a link 204, the other end of which is connected to a rod 205. The other end of the rod 205 is provided with a slot 206

into which extends a pin 207 supported at one end of a lever 208 which is fulcrumed at 209 and has its opposite end connected to the clutch collar 143 so that the clutch

5 may be thrown out when desired and a direct connection effected between the auxiliary motor 136 and the shaft 128 which is operatively connected to the work table to actuate it.

10 *The operation.*

The operation of my novel construction of multiple drill will now be readily apparent to those skilled in this art and is as 15 follows:—

The drill heads 94 and 100 are assembled in the desired spaced relation on the spindle carrying head 87 and the spacers 124 placed in position after which the nuts 125 are 20 tightened, see Figures 1 and 23. The stops 194 are secured in their proper position on the drum 190, see Figure 13, so that the work table will be intermittently actuated. Assuming now that the work, such as for

25 example, a boiler drum, has been clamped in position on the work table 6, the operator if he desires a rapid feed draws downwardly on the cable 73 thereby rocking the shaft 68, see Figures 28 and 26, and 30 causing the friction gear 71 to engage the friction gears 66 and 67, see more particularly Figure 29. This causes the shaft 27 to rotate the feed screws 77 which are intergeared with it, as will be understood by 35 reference to Figures 1, 2 and 20. As the feed screws 77 mesh with the nuts 80 carried by the cross rail 82, the cross rail 82 and its adjuncts will be raised or lowered depending upon the direction of rotation 40 of the feed screws 77 and as described the operation of the cable 73 will cause the cross rail 82 to be fed downwardly to effect the drilling or other operation which is to be performed.

45 In the usual operation of drilling as soon as the drills are brought into proper position with respect to the work, the operator actuates the lever 46 to rock the shaft 45 and cause the gear segment 44 to move the bar 42 in the proper direction to effect the rotation of the shaft 27 in one direction or the other, it being remembered that the shaft 27 is operatively connected to the feed screws to effect the raising and lowering of 50 the head on which the drill heads are mounted. If the slide rod 42, see Figure 29, is moved to the left, the clutch member 34 will engage the clutch member 33 and if the rod 42 is moved in a reverse direction, the clutch member 36 will engage the clutch member 37, see Figure 31. By such construction the shaft 23, which is operatively connected to the main driving motor 9 to be continuously driven thereby, can be operatively connected 55 with the shaft 27 to rotate in one direction

or the other and thereby effect the raising or lowering of the cross-head 82 on which is supported the spindle carrying-head 87 to which the drill heads are connected.

It will be understood that during the operation of the machine the main driving motor 9 causes the countershaft 13 to revolve and as this countershaft 13 is operatively connected by means of suitable belts and pulleys with the shaft of the spiral gear 103, such gear 103 is continuously revolved. This gear 103, see Figure 2, is intergeared with the spiral gear 98 so that the revolution of all of the drill spindles is effected, as will be understood by reference to Figures 1, 2, 3 75 and more particularly to Figures 20 and 25.

Where the spacing of the holes across the work is less than the minimum spacing of the drill spindles, the side movement of all the spindles is obtained by actuating the handle 91, see Figure 1, thereby rotating the feed screw 89 and effecting the lateral adjustment of the spindle carrying head 87, see Figures 21 and 22. The drill spindles may be spaced to suit any particular holes by shifting them along the cross rail formed by the spindle carrying head and clamping them in their adjusted position by means of the clamping screws 104, see more particularly Figure 25. By employing an inner and an outer spiral gear, such as 98 and 103, respectively, to drive the drill spindle, I am enabled to space the spindles much more closely together than would be possible if a single driving gear was employed for all 90 of the spindles.

In order to prevent improper movement or accidental displacement of the yoke 38 from the position to which it has been moved, I provide a stop member or arm 57, see Figures 26 and 30, and a holding device 60, see Figure 30, which latter bears against a roller 65. The stop arm 57 is normally maintained in its raised position by means of the spring 56, see Figure 26. When the handle 47 is actuated to move the slide bar 48 to the left, the cam face 50, see Figure 26, acting on the roller 53, draws downwardly the spring pressed plunger 54 and moves the stop arm 57 out of the path of the arm 58 which is connected to the yoke 38, see Figure 30, of the clutch mechanism which controls the operation of the clutch collar 25 which is keyed to the shaft 27.

110 *The operation of the table feeding mechanism.*

Referring now more particularly to Figures 1, 2, 3 and 5 to 19 inclusive, I will describe in detail the manner in which the feed of the work table 6 is effected. The cross rail 82 carries a latch or trip member 182 which moves in the path of a thrust member 181 secured to the bar 179, see more particularly Figure 3, 5, 6 and 12. When 120

the cross head 82 reaches the limit of its downward travel and the drilling operation is completed, the operator by actuating the arm or handle 46 operates the yoke 38 in the 5 feed gear box to cause the drill heads and their spindles to move upwardly as will be understood from the foregoing description.

The cross head 82, see more particularly Figure 5, is provided with a latch 182, which 10 travels in the path of the thrust member 181 secured to the bar 179, so that as the drill spindles and their adjuncts are moved upwardly, the bar 179 will be raised thereby rocking the free end of the lever 176 upwardly, see Figure 6, and causing the rod 174 to rock the shaft 171 and cause the rock arm 168, see Figures 12, 18 and 19, to move downwardly, thereby drawing downwardly the trigger or plunger 157 against the tension of the spring 158. This movement of the trigger or plunger 157 deflects the latch end of the shifting rod 146 downwardly, see more particularly Figures 7 and 8, thereby moving the cam shaped lug 151 out of the 25 path of a stop 194 on the drum 190.

As soon as the lug 151 is drawn downwardly out of the path of the stop 194 the compression spring 144, see Figure 7, causes the clutch member of the clutch collar 143 30 to engage the clutch member 170 of the gear 127 which is loosely mounted on the shaft 128, see more particularly Figure 10. This gear 127 as before explained is continuously revolved by the gear pinion 126 so that as soon as the clutch is closed in the manner 35 described, the shaft 128 begins to revolve thereby causing the gear 129 to rotate the gear 130 on the shaft 131 and as this shaft 131 is intergeared with the feed screws 134 40 which as best seen in Figure 11 passes through feed nuts carried by the work table 6, the work table is moved into its next position.

The shaft 128 has fixed to it the worm 185 45 which drives the worm gear 186 and thereby the shaft 187 see more particularly Figures 10, 12 and 17. This shaft 187 is keyed to the sleeve 188 which works in a fixed nut 189, so that a lateral movement of the drum 50 190 is effected during its revolution.

As soon as the next stop 194 on the drum 190 comes into the path of the lug 151 on the shifting rod 146, see Figure 8, it engages such lug and moves the shifting rod 55 146 rearwardly or to the left of the position seen in Figure 7 and brings its free end into position so that the trigger 157 will retain such free end in its raised position with the lug 151 in engagement with the stop 194. 60 The spring pressed latch 160 passes by the end of the shifting rod and the flange 166 carried by the trigger 157 prevents the downward movement of the free end of the shifting rod until it is again tripped, it 65 being understood that at this time the spring

158 is holding the trigger 157 in its raised position. The shifting rod 146 in its rearward movement moves the clutch collar 143 into its inoperative position so that there is no operative connection at this time between the gear 127 and the shaft 128. The feed of the table is thus stopped until the shifting rod is again tripped in the manner before described.

If a quick return of the work table 6 to its forward position is desired, the handle 142 is actuated thereby throwing in the clutch collar 140, so that the auxiliary motor 136 is directly connected with the shaft 128. This lever 142 is also connected with the clutch collar 143, see Figures 3 and 6, so that such clutch collar 143 is actuated at the same time. The pin and also connection 207 and 206 permits the proper actuation of the clutch collar 143 when the shifting rod is tripped automatically by the upward movement of the cross head 82. It will be seen from Figure 5 that the top face of the thrust member 181 is beveled and the latch 183 is provided with a cam face on its under side so that it can pass by the thrust member 181 as the cross head 82 moves downwardly during the drilling operation.

It will be apparent that in accordance with my present invention the drills or other working tools can be adjusted to conform to any desired lay out of the holes on the work either by inserting or removing certain of the drills by adjusting the position of the drill head or by lateral movement of the drill head support or cross rail 87.

It will now be apparent that I have devised a novel and useful construction of a multiple spindle drill which embodies the features of advantage enumerated as desirable in the statement of the invention and the above description, and while I have, in the present instance, shown and described a preferred embodiment thereof which will be found in practice to give satisfactory and reliable results, it is to be understood that the same is susceptible of modification in various particulars without departing from the spirit or scope of the invention or sacrificing any of its advantages.

Having thus described my invention what I claim as new and desire to secure by Letters Patent, is:

1. The combination with a work table, of a shaft operatively connected with it to feed it, a clutch comprising a continuously revolving member loose on said shaft and a member keyed to said shaft, a shifting rod connected to said keyed member, a drum driven by said shaft and having a stop to move said shifting rod to open the clutch members, a spring to effect the closing of said members, and means to move said shifting rod out of the path of said stop to permit said spring to close said clutch members. 125 130 135 140 145 150 155 160 165 170 175 180 185 190 195 200 205 210 215 220 225 230 2. The combination with a work table, of a shaft operatively connected with it to feed it, a clutch comprising a continuously revolving member loose on said shaft and a member keyed to said shaft, a shifting rod connected to said keyed member, a drum driven by said shaft and having a spiral groove, a series of stops positioned in said groove and adapted to move said shifting rod to open the clutch members, a spring to effect the closing of said members, and means to move said shifting rod out of the path of said stop to permit said spring to close said clutch members. 65
- 5 3. The combination with a work table, of a shaft operatively connected with it to feed it, a clutch comprising a continuously revolving member loose on said shaft and a member keyed to said shaft, a shifting rod connected to said keyed member, a drum driven by said shaft and having a spiral groove in its periphery, stops positioned in said groove, a member on said shifting rod in the path of said stops and engaged thereby to move the shifting rod to open the clutch members, a spring to effect the closing of said members, and means to move said shifting rod out of the path of said stops to permit said spring to close said clutch members. 70
- 10 4. The combination with a work table, of a shaft operatively connected with it to feed it, a clutch comprising a continuously revolving member loose on said shaft and a member keyed to said shaft, a shifting rod connected to said keyed member, a drum driven by said shaft and having a spiral groove in its periphery, stops positioned in said groove, a member on said shifting rod in the path of said stops and engaged thereby to move the shifting rod to open the clutch members, a spring to effect the closing of said members, and means to move said shifting rod out of the path of said stops to permit said spring to close said clutch members. 75
- 15 5. The combination with a work table, of a shaft operatively connected with it to feed it, a clutch consisting of a driven member loose on said shaft and a member keyed to said shaft, a shifting rod connected to said keyed member, a drum rotated by said shaft, means to cause said drum to move laterally during its rotation, stops carried by said drum and adapted to move said shifting rod to open the clutch members, a spring to effect the closing of said members, and means to move said shifting rod out of the path of said stop to permit said spring to operate to close said clutch members. 80
- 20 6. The combination with a work table, of a shaft operatively connected with it to feed it, a clutch consisting of a driven member loose on said shaft and a member keyed to said shaft, a shifting rod connected to said keyed member, a drum driven by said shaft, stops on said drum co-operating with said shifting rod to actuate it, a spring pressed trigger to retain said shifting rod in position to be engaged by said stop, and means to move said trigger into its inoperative position. 85
- 25 7. The combination with a work table, of a shaft operatively connected with it to feed it, driving means for said shaft including a clutch, a shifting rod connected to said clutch to actuate it, a spring to close said clutch, a drum driven by said shaft, stops on said drum co-operating with said shifting rod to actuate it, a spring pressed trigger to retain said shifting rod in position to be engaged by said stop, and means to move said trigger into its inoperative position. 90
- 30 8. The combination with a work table, of feeding means for it including a clutch, a spring to move said clutch in one direction, a shifting rod to move the clutch in the opposite direction, a drum rotated by said feeding means, stops on said drums, means to cause said drum to travel laterally and bring said stops into position to actuate said shifting rod, and means to move said shifting rod into position to render it inoperative with respect to said stops. 95
- 35 9. The combination with a work table, of feeding means for it including a clutch, a spring to move said clutch in one direction, a shifting rod to move the clutch in the opposite direction, means to actuate said shifting rod, a spring pressed trigger to move said shifting rod into and out of its operative position, an automatically actuated rock shaft, and a rock arm carried by said shaft and actuating said trigger. 100
- 40 10. The combination with a work table, of feeding means for it including a clutch, a shifting rod to open said clutch, a spring supported trigger having means to engage the end of the shifting rod to retain it in its operative position, means to actuate said shifting rod when in such position, a laterally movable spring pressed plunger carried by said trigger to engage said rod to cause it to move with said trigger, and a mechanically actuated trip for said trigger. 105
- 45 11. The combination with a reciprocatory spindle carrying member and means to actuate it, of a work table, a continuously driven clutch member, a shaft operatively connected with said work table to feed it, a second clutch member on said shaft, yielding means to move said second clutch member into engagement with said first clutch member, and shifting mechanism automatically controlled by said spindle carrying member to move 110
- 50 12. The combination with a reciprocatory spindle carrying member and means to actuate it, of a work table, a continuously driven clutch member, a shaft operatively connected with said work table to feed it, a second clutch member on said shaft, yielding means to move said second clutch member into engagement with said first clutch member, and shifting mechanism automatically controlled by said spindle carrying member to move 115
- 55 13. The combination with a reciprocatory spindle carrying member and means to actuate it, of a work table, a continuously driven clutch member, a shaft operatively connected with said work table to feed it, a second clutch member on said shaft, yielding means to move said second clutch member into engagement with said first clutch member, and shifting mechanism automatically controlled by said spindle carrying member to move 120
- 60 14. The combination with a reciprocatory spindle carrying member and means to actuate it, of a work table, a continuously driven clutch member, a shaft operatively connected with said work table to feed it, a second clutch member on said shaft, yielding means to move said second clutch member into engagement with said first clutch member, and shifting mechanism automatically controlled by said spindle carrying member to move 125

- said second clutch member out of engagement with said first clutch member.
12. The combination with a reciprocating spindle carrying member and means to actuate it, of a work table, a continuously driven clutch member, a shaft operatively connected with said work table to feed it, a second clutch member on said shaft, yielding means to move said second clutch member into engagement with said first clutch member, and shifting mechanism automatically controlled by said spindle carrying member to intermittently move said second clutch member out of engagement with said first clutch member.
13. The combination with a reciprocating spindle carrying member and means to actuate it, of a work table, a continuously driven clutch member, a shaft operatively connected with said work table to feed it, a second clutch member on said shaft, yielding means to move said second clutch member into engagement with said first clutch member, shifting mechanism automatically controlled by said spindle carrying member to move said second clutch member out of engagement with said first clutch member, an auxiliary motor, a manually controlled clutch to connect said shaft to said auxiliary motor, and a connection from said manually controlled clutch to simultaneously actuate said second clutch member, said connection including a pin and slot arrangement whereby said second clutch member can be automatically actuated without affecting said manually controlled clutch.
14. The combination with a reciprocating spindle carrying member and means to actuate it, of a work table, a continuously driven clutch member, a shaft operatively connected with said work table to feed it, a second clutch member on said shaft, yielding means to move said second clutch member into engagement with said first clutch member, shifting mechanism automatically controlled by said spindle carrying member to move said second clutch member out of engagement with said first clutch member, an auxiliary motor, a manually controlled clutch to connect said shaft to said auxiliary motor, and a connection from said manually controlled clutch to simultaneously actuate said clutch member.
15. The combination with a reciprocating spindle carrying member and means to actuate it, of a work table, a continuously driven clutch member, a shaft operatively connected with said work table to feed it, a second clutch member on said shaft, yielding means to move said second clutch member into engagement with said first clutch member, shifting mechanism automatically controlled by said spindle carrying member to move said second clutch member out of engagement with said first clutch member, an auxiliary motor, a manually controlled clutch to connect said shaft to said auxiliary motor, and a connection from said manually controlled clutch to simultaneously actuate said second clutch member, said connection including a pin and slot arrangement whereby said second clutch member can be automatically actuated without affecting said manually controlled clutch.
16. The combination with a reciprocating spindle carrying member and means to actuate it, of a work table, a shaft operatively connected with said work table, to feed it, a continuously driven member, a clutch to form an operative connection between said driven member and said shaft, a shifting rod controlling said clutch, a lug on said shifting rod, a spring pressed trigger normally in position to receive the free end of said rod, a clutch actuating member intergeared with said shaft and having means movable in the path of said lug to actuate said shifting rod in a direction to open said clutch, and means controlled by said spindle carrying member to actuate said trigger to move the shifting rod and thereby its lug out of the path of said means.

FRANK EGON NEITZEL.
